UNITED STATES PATENT OFFICE.

FREDERICK NEVINS, OF BROOKLYN, NEW YORK, AND WILLIAM B. MOREWOOD, OF ELIZABETH, NEW JERSEY; SAID NEVINS ASSIGNOR TO SAID MOREWOOD.

SUPPORTING TERMINAL CLIP.

No. 872,741.

Specification of Letters Patent.

Patented Dec. 3, 1907.

Application filed April 27, 1907. Serial No. 370,712.

To all whom it may concern:

Be it known that we, FREDERICK NEVINS and WILLIAM B. MOREWOOD, both citizens of the United States, and residents, respectively, 5 of the borough of Brooklyn, county of Kings, State of New York, and of the city of Elizabeth, county of Union, State of New Jersey, have invented certain new and useful Improvements in Supporting Terminal Clips, of 10 which the following is a specification.

This invention relates to supporting devices and more particularly to such as are designed and adapted for supporting a man when standing on a window ledge.

15 The object of the invention is to furnish an efficient and reliable terminal supporting clip for securing the end of a belt strap to a single wall bolt.

20 More particularly, it is the object of the invention to furnish such a clip as may be manually applied to and removed from the bolt with convenience and despatch and which, when applied to the bolt, will be locked against accidental disengagement with the 25 bolt.

The above and further objects will be apparent from the following description.

A preferred embodiment of the invention is illustrated in the accompanying drawings, 30 which form a part of this specification, in which like numerals indicate corresponding parts, and in which,—

Figure 1 is a sectional elevation of a clip in combination with a wall bolt shown in elevation; Fig. 2 is a horizontal section taken along line 2—2 of Fig. 1 and showing the wall bolt in plan; and Fig. 3 is a rear elevation of the clip showing a belt strap secured to the eye of the clip.

40 Referring now more particularly to the drawings, 1 indicates the terminal supporting-clip and 2 indicates the wall bolt. The wall bolt 2 comprises a web-like shank 3, to be located in the interstices between bricks 45 of a building construction; a projecting neck 4; and an enlarged head 5, which may preferably be square, as indicated in the drawings.

The clip 1 and the bolt 2 may each preferably be cast as an entirety in bronze or other suitable metal. The clip 1 comprises a base member 6, sides 7 and 8, an end closure 9 and a top closure 10. As shown in Fig. 1, the lower extremities of the base member 6 and 55 the sides 7 and 8 are outwardly offset and

terminate in an eye 11 to which may be secured the end of a belt strap 12. The base member 6 is provided with a longitudinal slot 13 which extends from the side of the bolt head opening 14 located near the eye 60 end of the clip to a curved wall 15 at the terminal end of the clip. The slot 13 opens into a longitudinal channel 16 extending between the sides 7 and 8 and of substantially uniform cross section throughout its length from the 65 bolt head opening 14 to its opposite end 17.

The bolt head opening 14 may preferably be square to conform to the contour of the bolt head 5 and as illustrated. Furthermore, this bolt head opening may preferably 70 be of a size to permit the passage therethrough of the bolt head 5 only when the square faces of the bolt head are parallel with the square walls of the opening 14. The width of the channel 16 may be such that 75 the bolt head 5 may pass freely therethrough in any position, the edges of the slot 13 always keeping the bolt head 5 clear of the sides 7 and 8 and the end closure 9. A curved wall 15 forms the end closure for the 80 slot 13 and is designed to engage the neck 4 of the bolt 2 so that the clip 1 may swivel about the bolt head 5 and be secured in a manner similar to a ball and socket joint.

The longitudinal top closure 10 for the 85 channel 16 is offset at 18 to permit a gate 19 to be swung clear of the channel 16. The gate 19 is pivotally supported by the clip and constitutes automatic means for preventing the accidental exit of the bolt head 90 from the channel 16. As shown, the gate 19 is pivoted upon a pin 20 piercing the sides 7 and 8 and forms pivoting means. The gate 19 is arranged to rest against a back stop to prevent its outward swing. As illustrated, 95 this stop is formed by two shoulders 21 and 22 at the entrance of the channel 16. The gate 19 is preferably provided with a finger engageable lip 23 for manually swinging the gate 19 out of the channel 16 into the position shown in dotted lines in Fig. 1. Suitable provisions are provided to hold the gate 19 against the shoulders 21 and 22 when the clip is in upright position. These provisions may be in the form of a spring 24 105 or the pivoting of the gate so that gravity will tend to hold the gate in closing position against the shoulders 21 and 22, when the clip is in upright position.

The clip 1 may be applied to the bolt 2 110

with convenience and despatch by workmen, it being necessary for them to employ but one hand for the operation. This is likewise true of the manual removal of the clip 1 from the bolt 2.

To attach the clip to the bolt, the clip 1 is held in an upright position and applied to the bolt head 5 so that the bolt head passes out through the bolt head opening 14. A downward pressure then causes the bolt head 5 to engage the pivoted gate 19, which swings up into the position shown in dotted lines in Fig. 1 allowing the bolt head 5 to pass up through the passage 16 until the curved wall 15 engages the neck 4 upon which the clip may work with the freedom provided in a ball and socket joint. As soon as the bolt head has passed the gate 19, the gate moves into the position illustrated to lock the clip 20 against accidental removal from the bolt head 5. If, by any accident, as by a blow, the clip 1 should be moved upwardly, the bolt head 5 would strike against the gate 19, which would prevent the neck 4 being disengaged by the slot 13.

To remove the clip 1 from the bolt head 5 the clip may be grasped by one hand, moved upwardly, and, by the engagement of one finger with the lip 23, the gate 19 may be moved into the position shown in dotted lines, when a further upward movement of the clip 1 brings the bolt head 5 into alignment with the bolt head opening 14 and an outward movement of the clip 1 causes the passage of the bolt head 5 through the bolt head opening 14 and the complete removal of the clip 1.

Although a preferred embodiment of the invention has been illustrated and described, it is obvious that modifications of the same may be made within the scope of the invention.

Although the sides 7 and 8 and the end and top closures 9 and 10 are preferred, they are not essential to the proper operation of the clip. The base member 6 suitably strengthened and provided with the slot 13 and a suitable top to prevent the exit of the bolt neck form alone a desirable clip.

What is claimed and what is desired to be secured by Letters Patent is:—

1. A supporting terminal clip comprising an eye at one end; sides providing a longitudinal channel therebetween; a base member provided with a longitudinal slot connecting with said channel and provided with a bolt head opening for the eye end of said slot; a bolt neck engaging wall for the terminal end of said slot; a gate comprising a rigid plate normally extending across said channel at the end near said bolt head opening; pivoting means for said gate; a stop for said gate to prevent the outward swing thereof and the accidental exit of the bolt head from said channel but permitting the automatic in-

ward swing of said gate to clear the bolt head upon its entrance and permitting the readily manually effected inward swing of said gate so that the clip may be released and removed by one hand alone.

2. In combination, a wall bolt comprising a neck and an enlarged head, with a supporting terminal clip comprising an eye at one end; sides providing a longitudinal channel therebetween; a base member provided with a longitudinal slot connecting with said channel and provided with a bolt head opening for the eye end of said slot; a bolt neck engaging wall for the terminal end of said slot; a longitudinal closure for the top of said channel; a gate comprising a rigid plate normally extending across said channel at the end near said bolt head opening; pivoting means for said gate; a stop for said gate to prevent the outward swing thereof and the accidental exit of the bolt head from said channel but permitting the automatic inward swing of said gate to clear the bolt head upon its entrance and permitting the readily manually effected inward swing of said gate so that the clip may be released and removed by one hand alone.

3. A supporting terminal clip comprising an eye at one end; sides providing a longitudinal channel therebetween; a base member provided with a longitudinal slot connecting with said channel and provided with a bolt head opening for the eye end of said slot; a bolt neck engaging wall for the terminal end of said slot; a gate comprising a rigid plate normally extending across said channel at the end near said bolt head opening; pivoting means for said gate secured to said sides at a greater distance away from said base member than the thickness of the bolt head; a stop for said gate to prevent the outward swing thereof and the accidental exit of the bolt head from said channel but permitting the automatic inward swing of said gate to clear the bolt head upon its entrance and permitting the readily manually effected inward swing of said gate so that the clip may be released and removed by one hand alone.

4. A supporting terminal clip comprising an eye at one end; sides providing a longitudinal channel therebetween; a base member provided with a longitudinal slot connecting with said channel and provided with a bolt head opening for the eye end of said slot; a bolt neck engaging wall for the terminal end of said slot; a longitudinal closure for the top of said channel; a gate comprising a rigid plate normally extending across said channel at the end near said bolt head opening; pivoting means for said gate secured to said sides at a greater distance away from said base member than the thickness of the bolt head; a stop for said gate to prevent the outward swing thereof and the accidental exit of the bolt head from said channel but per-

mitting the automatic inward swing of said gate to clear the bolt head upon its entrance and permitting the readily manually effected inward swing of said gate so that the clip 5 may be released and removed by one hand alone.

5. A supporting terminal clip comprising an eye at one end; sides providing a longitudinal channel therebetween; a base member 10 provided with a longitudinal slot connecting with said channel and provided with a bolt head opening for the eye end of said slot; a bolt neck engaging wall for the terminal end of said slot; a gate; pivoting means for said 15 gate engaging said sides between said bolt head opening and said socket; a stop to prevent the outward swing of the gate, said gate being arranged to engage said stop, permitting the entrance of the bolt head into the 20 channel but preventing its accidental exit from the channel; and a finger engageable lip extending outwardly beyond said pivot- 25 ing means for swinging said gate inward to permit the exit of the bolt head from the channel, all forming a clip capable of ready application and removal by one hand alone.

6. A supporting terminal clip comprising an eye at one end; sides providing a longitudi-

dinal channel therebetween; a base member provided with a longitudinal slot connecting 30 with said channel and provided with a bolt head opening for the eye end of said slot; a bolt neck engaging wall for the terminal end of said slot; a longitudinal closure for the top of said channel; a gate; pivoting means for 35 said gate engaging said sides between said bolt head opening and said socket; a stop to prevent the outward swing of the gate, said gate being arranged to engage said stop, permitting the entrance of the bolt head into the 40 channel but preventing its accidental exit from the channel; and a finger engageable lip extending outwardly beyond said pivot- 45 ing means for swinging said gate inward and toward said top closure to permit the exit of the bolt head from the channel, all forming a clip capable of ready application and removal by one hand alone.

In testimony whereof, we have signed our names to this specification, in the presence of 50 two subscribing witnesses.
